UNITED STATES PATENT OFFICE.

JAMES PRESCOTT WALES, OF MEMPHIS, TENNESSEE.

TRUNK-BINDER.

SPECIFICATION forming part of Letters Patent No. 726,806, dated April 28, 1903.

Application filed November 13, 1902. Serial No. 131,281. (No model.)

To all whom it may concern:

Be it known that I, JAMES PRESCOTT WALES, a citizen of the United States, residing at Memphis, in the county of Shelby and State of Tennessee, have invented a useful Article for Binding Trunks and Boxes of Value While in Transit, of which the following is a specification.

My invention relates to improvements in binders for trunk, boxes, or the like, and it will be understood by reference to the accompanying drawings, in which the same parts are indicated by the same letters throughout both views.

Figure 1 is a perspective view of a trunk having my improved binder fitted thereto. Fig. 2 is a perspective view of the tightening device as seen from the opposite side from that shown in Fig. 1.

A represents the trunk.

B represents the plurality of wires, which are looped, as at b, to engage the corners of the trunk. The size of said loops may be varied at will, and the loop may be separate from or secured to the wire B, as preferred.

C represents the tightener, which consists of a hub C', having posts c, projecting from this hub, and the arm C⁰, which arm terminates in the curved tongue c², provided with holding-teeth c³. This tongue projects under one of the wires, as shown in Fig. 1. The said wires are secured to or pass over the posts c.

It will be seen that by twisting the arm C⁰ to the left from the position shown in Fig. 1 the various wires will be tautened until when the desired tension is secured one of the teeth c³ engages in the corresponding wire and automatically locks the binder at the desired position. To release the same, it will only

be necessary to spring the wire out of engagement with the teeth of the tongue and ease up on the arm C⁰. It will be obvious that one or more turns or parts of turns may be taken with the arm C⁰, so that the desired degree of tautness on the wires may be obtained, this being limited to the strength of the posts or of the wires themselves.

I do not mean to limit my invention to the precise details of construction herein described and shown, for various modifications might be made which could be used without departing from the spirit of my invention.

Having thus described my invention, what I claim, and desire to secure by Letters Patent of the United States, is—

1. The combination with a plurality of wires looped to pass over the corners of a trunk or box, of a tautening device, consisting of a hub provided with posts engaging said wires, an arm for turning said hub, and means for locking said arm at the desired position, substantially as described.

2. The combination with a plurality of wires looped to pass over the corners of a trunk or box, of a tautening device, consisting of a hub provided with posts engaging said wires, an arm for turning said hub, and a curved tongue provided with teeth connected to said arm and engaging one of said wires, substantially as and for the purposes described.

In testimony whereof I have signed my name to this specification in the presence of two subscribing witnesses.

JAMES PRESCOTT WALES.
